UNITED STATES PATENT OFFICE.

EMILE BRACQ-LAURENT, OF PARIS, FRANCE.

HELICAL-HEARTH FURNACE.

Application filed April 20, 1922. Serial No. 555,735.

To all whom it may concern:

Be it known that I, EMILE BRACQ-LAURENT, a citizen of the Republic of France, residing in Paris, France, have invented 5 certain new and useful Improvements in Helical-Hearth Furnaces, of which the following is a specification.

This invention relates to improvements in furnaces with helical hearths, utilized for 10 roasting sulphurous or other ores, drying or the like, in which perfect roasting is obtained by successive division into and advance in layers of, the material to be roasted on the helical hearths, this division and this 15 advance being obtained by means of scraper arms having a reciprocating motion and rising and descending movements limited in their advance, obtained by various means known by previous patents.

20 This invention comprises a construction by means of which the various movements may be produced, the number of mechanical elements in the said construction being reduced to a minimum, whilst at the same 25 time ensuring efficient operation of the furnace, and reduction of the supervision and upkeep of the parts.

The construction according to this invention is shown in the accompanying drawings in which—

30 Figure 1 is an elevation, partly in section of the upper part of the furnace where the whole of the operating mechanism is arranged, and

35 Figure 2 is a plan looking from the top of the rotating platform supporting the mechanism.

Fig. 3 is a detail sectional elevation and Fig. 4 a detail elevation of certain 40 portions of the device.

In helical hearth furnaces designed by the applicant, the central shaft 1 carrying the scraper arms 2 revolving the material in the furnace, receives all its movements 45 from a shaft 3 forming an extension of the central shaft 1 and placed outside the furnace, either at the top or at the bottom, according to the arrangement adopted.

This device still remains the same, but 50 according to this invention a rotating platform 5 provided at the circumference with helical teeth 6 meshing with a worm 7 is mounted on a fixed circular frame 4. On the top of the said platform 5 is mounted 55 an electric motor 8 which drives, by means

of a worm, a worm wheel 9, (Figure 2) enclosed in a case 10 and mounted on the horizontal spindle 11. This spindle is supported in two bearings 12 and 13 mounted on the rotating platform 5, and produces 60 two movements which are transmitted to the shaft 3, and consequently to the central shaft 1 and scraper arms 2, 2' secured to the shaft 3.

By means of a crank disc 14, connecting 65 rod 15 and a guide-support 16, an angular movement is produced the extent of which can be modified by shifting the position of the adjustable crank pin 17. The rod 15 is connected to a bridle 18 which, by means 70 of two fixed projections 19 and 19 sliding in two straight vertical grooves 20 provided in the shaft 3, transmits to the latter the angular movement imparted to it by the connecting rod 15 attached to the 75 crank pin 17.

The second movement produced by the spindle 11, raises and lowers the shaft 3 and consequently the central shaft 1 and its scraper arms by means of an eccentric 21, 80 the rod 22 of which drives by means of its head 23, a rocker 24 with trunnions 26. The trunnions 26 are mounted in a collar 27 rotating between the flanges of a large nut 28 screwed on the shaft 3 which is provided 85 with helical grooves 29 which constitute a kind of thread of the same pitch as that of the refractory hearths in the interior of the furnace, on which are stirred and moved the materials under treatment. 90

The rocker 24 oscillates on a pin 25 which is common to the lever 40, the said pin resting at its ends on supports secured below the circular rim or platform 5.

95 The nut 28 is prevented from moving circularly by two rods 30 secured to it and sliding in two fixed guides 31. The said nut, however rises and descends on being operated by the rocker 24.

The nut 28 has a thread corresponding 100 to the grooves 29, in the same manner as the thread of a bolt nut, and the said thread enters the helical groove 29.

It will be understood from the preceding that at each revolution of the eccentric 21, 105 the large nut 28, the threads of which engage with the helical grooves 29 of the shaft 3, will raise and lower the grooved shaft 3 and therefore the central shaft 1 with its arms 2. 110

Obviously, if the nut 28 is caused to rise or descend by means of the rocker 24, the central shaft 1 carrying the arms 2 and rigidly secured to the shaft 3 must necessarily follow the movement imparted.

It will be seen, therefore, that in this device a single shaft 11 produces two essential movements imparted to the grooved shaft 3 and consequently to the central shaft 1 with its arms 2 and 2', firstly, the angular movement, and secondly, the up and down movement. A third movement however, takes place simultaneously which movement is the progressive raising and lowering of the central shaft 1 during the first two movements described, in "harmony" with the pitch of the refractory hearth of the furnace through which it has to travel, which pitch is similar to that inscribed on the grooved shaft 3.

The worm 7 which drives the helical teeth 6 of the circumference of the rotating platform 5, is driven by the spindle 32 to which it is keyed and which is driven by pulleys 25, 33 and 34 the direction of movement being reversed by means of clutches operatively connected to a rod 36. This worm 7 rotates the platform 5 which carries the bridle 18 which rotates the shaft 3.

30. The nut 28 which cannot rotate on account of the fixed guides 30 and 31, forces the grooved shaft 3 to rise or descend according as the bridle 18 screws or unscrews it.

35. The direction is reversed by means of tappets 37 and 38 suitably arranged so as to act on the clutches by the rods 36 and 35.

A principle of helical hearth furnaces is to stir and advance the material being roasted on the hearths during the upward movement of the scraper arms 2 and 2'. At the end of this movement, the direction of rotation of the platform 5 is reversed by means of the clutches and the pulleys 33 and 34, and the central shaft 1 effects a period of descent during which the up and down movements must cease, in order that the scraper arms 2 may cease their action which otherwise would be injurious.

50. Moreover it is necessary that the scrapers 2 and 2' lowered with the shaft 1, should in this downward movement be brought over the material which, in passing, they have treated and advanced. To that end the eccentric rod 22 is connected with its head 23 to a connecting rod 39 (Figure 1) connected to a lever 40 with a balance weight pivoted at 25 which is operated at the proper moment by a vertical rod 41 operated by a tappet 42 secured to the head of the grooved shaft 3.

The action of the connecting rod 22 which causes the central shaft 3 and the arms to rise and descend is stopped by means of the rod 41 provided with a tappet 44 which lat-

ter will tilt the lever 40 and this latter draws toward it the connecting rod 22 by the rod 39 and brings the crosshead 23 into the opening 43 where the action of the said rod on the rocker 24 is cancelled, the arms 2 being thus kept in the raised position. The opening 43 is provided in a separate part 39' on the rocker 24.

The vertical rod 41 is driven in an upward direction by the grooved shaft 3 to 75 which it is secured, so that the lever 40, the end of which is secured to the connecting rod 22, is turned by the tappets on the latter.

It is obvious that the rising and descending movements will be produced during the 80 whole rotation of the platform in order to displace the material in the furnace.

Without the electric motor, complicated mechanisms—such as are in fact used for known furnaces of the present kind—would be necessary to control the movements on a rotating platform, so that the idea of using an electric motor constitutes a great improvement.

During the rise and descent, the head 23 90 strikes against the portion b, b' of part 39' and as the said part 39' is integral with the rocker 24, the latter is compelled to rise and descend at each revolution of the connecting rod 22. However, when the head 23 of the rod 22 is drawn into the opening 43 by the rod 39, its action is stopped as before stated and the rocker 24 rendered immovable in any desired position by the stops of the nut 28.

It should be understood that the rod 22 moves in the centre of the two lateral parts of the opening 43.

A, A', are the ends or journals of the cross-head, which ends are pivoted to the rod 22 105 and normally rest on part B, B' of the part 39', and which are then released in the lateral opening 43 when it is desired to stop the action of the connecting rod 22.

In fact, whenever the eccentric 21 descends, it lowers with the head 23 the rocker 24 which thus raises the arms 2 above the material being treated during the period of descent, whilst whenever the eccentric pulley 21 rises, its action is cancelled by the head 23 moving in the opening 43 into which it has been brought by the rod 41 and the connecting rod 39.

This movement of the eccentric rod 22 and its head 23 operative or inoperative is thus obtained in a practical and reliable manner, with great facility of regulation or adjustment, and with a minimum number of parts.

This movement may be obtained in every case, whether there be one or more helical hearths, or whether there be a greater or less number of scraper arms 2 between which the rotation of the grooved shaft 3 is divided. Owing to the operation of the tappet 130

42, the action or inaction of 22 and 23 depends on the desired up or down movement of the shaft 3.

It is further possible to produce by the 5 bottom end of the rod 41 the throwing into or out of gear of the pulleys 33 and 34 by means of the clutches on which the rod 41 acts by means of bell crank levers.

What I claim as my invention and desire 10 to secure by Letters Patent is:

1. In a furnace with a helical hearth having a central shaft, a rotating platform, and scraper arms, means producing the angular movement and the up and down movement 15 of the central shaft, comprising a single spindle driven by an electric motor mounted on the rotating platform of the furnace.

2. In a furnace as claimed in claim 1, 20 means for producing the angular movement, comprising a crank disc mounted at one end of a driving spindle and having a crank pin the position of which may be adjusted to suit the amplitude of movement to be transmitted, the said movement being transmitted to a bridle provided with two projections 25 engaging with two corresponding grooves of the shaft and thus transmitting the movement to it.

3. In a furnace as claimed in claim 1, 30 means for producing the up and down movement of the shaft, and scraper arms, comprising an eccentric mounted on the single driving spindle and operating a rocker, one 35 of the trunnions of which is secured to a collar rotating about a large nut which is adapted to slide round the shaft but cannot rotate, the said nut by its rise or descent rotating the said shaft and consequently rais-

ing or lowering the shaft carrying the 40 scraper arms.

4. In a furnace of the character described, the combination with a central shaft, and scraper arms thereon, of a rotatable platform provided with circumferential helical 45 teeth, a worm engaging with said teeth to effect the rotation of the platform, means for rotating the worm in either direction, and means for producing an angular movement and an up and down movement of the 50 central shaft comprising a single spindle driven by an electric motor mounted on the said platform.

5. In a furnace of the character described, the combination with a central shaft and 55 scraper arms thereon, of means for producing an angular movement and an up and down movement of the central shaft, and means for effecting the descent of the shaft and of the scraper arms automatically comprising a tappet secured to the shaft, an eccentric, a rod operated thereby, a rocker operated by said eccentric rod, a pivoted lever carrying a balance weight, a connecting rod between the weighted lever and the eccentric 60 rod, and a vertical rod operated by the aforesaid tappet, the said pivoted lever being operated by the said vertical rod so as to cancel the movement of the aforesaid connecting rod.

In testimony whereof I have signed my name to this specification in the presence of two subscribing witnesses.
